UNITED STATES PATENT OFFICE.

ALFRED G. F. KUROWSKI, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed March 31, 1924. Serial No. 703,087.

This invention relates to improvements in portable typewriting machines, and particularly to the carriage-operating mechanism.

A feature of the invention is the provision of back-spacing mechanism including a pawl effective to engage and move the escapement-wheel sufficiently to permit the stepping dog of the carriage-feeding mechanism to trip over one tooth of the escapement-wheel and assume a position for engagement with the next successive tooth of the wheel, an abutment being provided for positively limiting the throw of the pawl. The pawl also acts as a brake against the wheel.

Another feature is the provision in such mechanism of a back-spacing pawl positioned and supported to move along a direct path substantially tangential to the wheel, the camming action of the teeth of the wheel, freeing the pawl on the return stroke thereof away from the wheel.

The case-shift frame is inclined, and, in order to operate the back-spacing pawl in different case-type positions, there are provided a novel key and a linkage between the key and said back-spacing pawl, forming a further feature of the invention.

Other features and advantages will hereinafter appear.

In the accompanying drawings,

Figure 1 is an approximate central vertical section of the improved machine.

Figure 2 is an end elevation, looking from the left, with parts of the frame broken away.

Figure 3 is a front elevation of the escapement device and connections.

Figure 4 is a plan view of Figure 3.

Figure 5 is a detail of the carriage-motor.

Figures 6 and 7 are diagrammatic views, showing the back-spacing mechanism and co-operating parts in their several positions.

In the present embodiment of the invention, the frame of the improved machine, indicated generally at 1, has the usual key-levers 2 which operate type-bars 3 through connections comprising bell-crank 4, and links 5, the bell-crank pivoted on a common support 6 by means of a fulcrum rod 7. The type-bars are pivotally mounted on a fulcrum rod 8 carried by a segment 9 which, as shown, is inclined rearwardly towards its top. A type-bar rest 10 is provided for engagement by the type-bars in rest position,

and the usual platen 11, mounted in a carriage 12, is arranged above and behind the segment.

The carriage is mounted to move longitudinally in a carriage shift-frame 13, and bearings 14 are arranged between the frame and the carriage, in races formed by bearing rails 15 on the carriage and co-operating rails 16 on the shift-frame. The shift-frame is supported by links 17 and 18 at 60 its ends for shifting movement in the printing plane of the type-faces to upper and lower case positions, and mechanism is provided for feeding the carriage with a step-by-step movement, said mechanism being 70 controlled by a universal bar 19.

This bar is mounted in a groove 20 in the rear face of the segment, and it is engaged by extensions 21 on the type-bars when the bars attain a vertical position. 75 Further movement of the bars toward printing position moves the universal bar rearwardly, and sets the feed mechanism, so that when the universal bar returns to its normal position the carriage feeds. 80

The carriage-feeding mechanism comprises an escapement wheel 22 journaled on the rear plate 23 of the shift-frame, and having rigid therewith a coaxial pinion 24 which is engaged by a rack-bar 25 supported 85 by levers 26 below the carriage-frame. By means of a finger-piece 27 journaled on the axle of the platen, the levers 26 may be operated to release the rack-bar from the pinion when desired. 90

The escapement wheel is controlled to feed by the usual spring motor 28, supported by a bracket 29 on the rear plate 23 of the shift-frame, and connected to the carriage by the usual strap, not shown. A stepping dog 30 95 normally checks the forward or feed movement of the escapement wheel, said dog being pivoted to a rocker 31, pivotally mounted on the rear plate 23. The rocker has a holding dog 32 which, when the rocker is 100 swung to move the stepping dog rearwardly out of the plane of the escapement wheel, is moved into engagement therewith. A spring 33 connected with the stepping dog swings the dog away from a stop 34 which 105 limits the movement of the stepping dog with the escapement wheel in its forward movement, and into position beyond that tooth of the wheel that is then in engagement with the holding dog, so that when the 110

rocker again moves forwardly the escapement wheel may move the distance of a tooth before the stepping dog again engages the stop.

- 5 Referring to Figures 3 and 6, it will be seen that the spring 33 is arranged to hold the stepping dog in neutral position, that is, in equipoise between the stop 34 and a position between the teeth of the wheel.
- 10 The rocker is operated by means of a member 35 pivoted to swing on an axis transverse to a swinging frame 36 which carries the universal bar. This frame is supported by links 37 at its rear, said links being pivotally connected to the frame of the machine, and to arms 38 extending rearwardly from the swinging frame. At its front end the swinging frame has a lug 39 which engages in an opening in the segment plate. The frame is thus supported for swinging movement by the lug, and by the links 37. The swinging member 35 is normally held in vertical position and in position to engage the rocker and move the
- 15 same rearwardly, when the universal bar is moved rearwardly, by means of a stop 40 and a spring 41, and the member has an adjustable shoe 42 which engages an arm 43 extending upwardly and outwardly from
- 20 the rocker.

The back-spacing mechanism includes a back-spacing pawl 44 having an outturned tooth-engaging lip 44^a and an extension 44^b, positioned apart from the escapement wheel, 35 and supported to move over a path tangential to the wheel. The pawl is pivoted to the upper end of an arm 45 which is pivoted at its lower end, as indicated at 46, to the rear plate 23 of the shifting frame. The pawl 44 is horizontal, and is so held by a stop 47 on the arm, and a spring 48 arranged between the arm and the pawl. The arm is held substantially vertical by means of a spring 49, and a stop 50. The spring is arranged between the arm and a fixed bracket 51 on the rear plate 23, and acts normally to hold the arm against the stop.

The arm is operated to move the pawl by means of a key-lever 52 pivoted to a bracket 53 forming part of the machine-frame. A link 54 connects the inner end of the lever with an arm 55 on the upper end of a shaft 56 pivoted in a bracket 57 on the frame, and the arm 55 is connected to the arm 45 which carries the pawl 44 by means of a link 57^a. It will be noted by referring to Figure 4 that the link 54 connects to the arm 55 between shaft 56 and the end of the arm, in such manner that when the link 54 is moved forwardly the arm 45 will be swung, to cause the back-spacing pawl to engage the teeth of the escapement wheel.

The case-shift frame shifts in a rearwardly-inclined plane, and it is necessary that the link 54 be effective to operate the

pawl 44 in either case-type position. For this purpose, the link 54 is formed with a double bend, as indicated at 54^a, then continued straight toward the key-lever 52, and then bent up to a point of attachment 52^a at the free end of the key-lever 52. During case-shifting, the outer end of the link 54 will be moved slightly about its point of attachment 52^a, but a depression of the key-lever 52 will invariably actuate said link 54.

In order to limit the stroke of the back-spacing pawl a stop 58, including an abutment 58^a, is provided. This stop is secured to the rear plate 23, and the abutment 58^a is in position to engage the end or extension 44^b of the pawl at the limit of its stroke, to positively check the same and the movement of the back-spacing key. In order to prevent overthrow of the escapement wheel through inertia of the carriage, mechanism 85 is provided for forcing the pawl into close engagement with the escapement wheel at the end of the stroke of the pawl, thereby to brake the movement of the wheel. This mechanism comprises a cam surface 59 extending outwardly and upwardly from the stop toward the pawl, and designed to engage the end of the pawl to guide said pawl and to force the same downwardly and into close engagement with the ratchet wheel. The spring 48 permits the pawl to be swung away from the ratchet wheel by the teeth on the return movement of the pawl.

It will be noted by reference to Figure 1, that the typing system of the machine is tilted rearwardly, so that the printing plane of the type-faces inclines rearwardly toward the top. The carriage-feeding mechanism, including the escapement wheel, the dog rocker, the pinion and the rack-bar, is inclined to operate in planes parallel with the printing plane. These mechanisms are supported by the rear plate 23 of the carriage shift-frame, which is inclined to support them at the proper angle. The universal bar is mounted to move perpendicular to the rear plate 23, and to the plane of the escapement wheel, and the mechanism which transmits the movement of the universal bar to the escapement rocker transmits such movement in the line of movement of the universal bar. The arrangement lessens the vertical distance between the carriage and the key-levers, and permits a decrease in the total height of the machine, since the carriage and the platen may be set lower than were the feeding mechanism arranged vertically.

Variations may be resorted to within the scope of the invention, and portions of the improvements may be used without others.

Having thus described my invention, I claim:

1. In a typewriting machine, the combination of a carriage, letter-feeding mecha-

nism for the carriage including an escapement-wheel and a stepping dog, a stop for limiting the letter-feeding movement of the stepping dog, a key, a pawl operable by depression of said key to engage and move the escapement-wheel, to back-space the carriage, an abutment engageable by said pawl for positively limiting the back-spacing movement of said pawl after the stepping dog has tripped over one tooth and assumed a position for engagement with the next successive tooth of the escapement-wheel, means for guiding said pawl against said abutment and also for forcing said pawl into frictional engagement with the escapement-wheel after the stepping dog has tripped to the aforesaid position, and means for releasing said pawl, thereby permitting the carriage-feeding mechanism to bring said escapement-wheel to stop position against said stepping dog.

2. In a typewriting machine, the combination of a carriage, letter-feeding mechanism for the carriage including an escapement-wheel and a stepping dog, an arm mounted adjacent said escapement-wheel, a key-lever, operating connections between the key-lever and the arm, a pawl pivoted adjacent the free end of said arm, said pawl including a tooth-engaging lip and a projection extending therebeyond in the direction of the pawl travel, stop-means for maintaining said pawl in a position substantially tangential to the escapement-wheel, said key-lever being effective to cause said lip to engage the teeth of the escapement-wheel and to rotate the same in back-spacing direction, whereby to cause the stepping dog to trip over one tooth of the escapement-wheel and assume a position for engagement with a new tooth thereof, and an abutment engageable by said projection for positively stopping the travel of said pawl after the stepping dog has reached the aforesaid position.

3. In a typewriting machine, the combination of a carriage, letter-feeding mechanism for the carriage including an escapement-wheel and a stepping dog, an arm pivoted adjacent the escapement-wheel, a key-lever, operating connections between the key-lever and the arm, a stop limiting the rearward position of the arm, resilient means holding said arm against the stop, a pawl pivoted adjacent the free end of said arm, stop-means including a spring maintaining said pawl on said arm in a position substantially tangential to the escapement-wheel, said key-lever operable to move said arm to cause the pawl to engage a tooth of the wheel and to rotate said wheel in back-spacing direction, the stepping dog being effective during such back-spacing operation to trip over one tooth of said escapement-wheel and assume a position for engagement with the next succeeding tooth, and a stop including

an inclined plate adjacent the end of the back-spacing travel of the pawl, said plate effective to force said pawl into braking engagement with the escapement-wheel and to lock the pawl against the stop until the key-lever is released, the carriage-feeding mechanism being effective to return the escapement-wheel to stop position with the stepping dog in engagement with the successive tooth of the escapement-wheel. 75

4. In a typewriting machine, a carriage and a carriage-shift-frame having a rear plate, carriage-feed mechanism including an escapement-wheel journaled on the plate, and mechanism independent of the wheel and supported by the plate for co-operating with the wheel to back-space the carriage, said mechanism including a pawl, a stop for limiting the stroke of the pawl, and means to force the pawl into braking engagement with the wheel as it engages the stop, said stop and means supported by the plate. 80

5. In a typewriting machine, carriage-feed mechanism including an escapement-wheel, a back-spacing pawl positioned apart from the wheel on a line tangential thereto and mounted to move along said line into engagement with the teeth of the wheel, and to be swung away from the wheel by the teeth thereof on the return stroke, a stop to limit the stroke of the pawl, and a cam-surface to force the pawl toward the wheel as it engages the stop thereby to brake the wheel. 95

6. In a typewriting machine, the combination of a platen, a carriage, a case-shift frame shiftable in a rearwardly-inclined plane, an escapement-mechanism including an escapement-wheel, a pawl operable to engage the teeth of said escapement-wheel to back-space the carriage, a key, and operating connections between said key and the pawl, said connections including a link having the outer end thereof directed upward, said operating key being fulcrumed to the frame of the machine and including an arm projecting upward from the fulcrum of said key, the free end of the upwardly-directed portion of said link being connected to the free end of said arm of the key, whereby depression of said key imparts motion to the link to actuate said pawl, in all case-type positions of the case-shift frame. 100

7. In a typewriting machine, the combination of a platen, a carriage, a case-shift frame shiftable in a rearwardly-inclined plane, an escapement-mechanism including an escapement-wheel, a pawl operable to engage the teeth of said escapement-wheel to back-space the carriage, a swingable arm upon which said pawl is mounted, a support on said case-shift frame, a lever having one end thereof pivoted to said support, a connection between the swingable arm and the free end of said lever, a back-spacing 110

key having a vertically-extending arm, and a link connected at one end to said lever at a point between the pivot and the free end thereof, said link extending forwardly from

5 said lever and terminating in a portion di-
rected upwardly, the free end of said arm

being connected to the end of said upward-
ly-directed portion of the link, whereby de-
pression of said key operates the pawl in
all case-type positions of the case-shift

10 frame.

ALFRED G. F. KUROWSKI.
